(57) **CLAIM**

The ornamental design for a buffet, as shown and described.

DESCRIPTION

FIG. 1 is a front view of a first embodiment of a buffet showing my new design;

FIG. 2 is a right side view thereof, the left side view being identical;

FIG. 3 is a top view thereof;

FIG. 4 is a front view of a second embodiment of a buffet showing my new design;

FIG. 5 is a right side view thereof, the left side view being a mirror image; and,

FIG. 6 is a top view thereof.

The broken lines in the drawings are environmental only and form no part of the claimed design.
